DRY SHAVING INSTRUMENT

Russell E. Benner, New York, N. Y., assignor, by
mesne assignments, to Remington Rand Inc.,
Buffalo, N. Y., a corporation of Delaware

Application November 10, 1937, Serial No. 173,795

13 Claims. (Cl. 30—43)

This invention relates to improvements on electric dry shavers of a type well known in the art, particularly to a device for disengaging the inner cutter separably from the outer cutter.

5 Electric dry shavers now in commercial use provide a shearing head with an inner cutter so mounted that it is rather difficult and tedious to remove. According to the teaching of the prior art, this object is achieved primarily by disengaging the entire shearing head from the motor casing.

It is the main purpose of this invention to avoid this difficulty and to afford a simple and inexpensive means for disengaging the inner 15 from the outer cutter without first removing the entire shearing head from its motor casing.

One of the objects of this invention is to provide an improvement in electric dry shavers that affords a quick and simple means for detaching 20 the inner from the outer cutter for cleaning purposes.

A further object of this invention is to provide resilient means in dry shavers of the well known type described whereby the inner cutter may be 25 disengaged from the outer cutter while the latter still remains secured to the motor casing.

Another object of this invention is to provide 30 detachable finger devices, easy to operate, affording a time saving means for removing the inner cutter of dry shavers well known in the art.

Other objects will appear from a full and detailed description of the drawings attached to this specification.

This invention resides in the combination, construction, arrangement and relative location of 35 parts, all as will be described in detail in the following specification in connection with the drawings, in which:

Fig. 1 represents a fragmentary end elevational 40 view of the device embodying this invention.

Fig. 2 is an end elevational view partly in cross section, revealing a portion of the casing with parts thereof broken away.

Fig. 3 is a sectional view of the device taken 45 substantially along line 3—3 of Fig. 2.

Fig. 4 is a view of the device substantially similar to that in Fig. 3 but showing the inner cutter partially removed.

50 Fig. 5 is a sectional view of the device taken substantially along line 5—5 of Fig. 3.

Fig. 6 is a cross sectional view of a modified form of the device.

55 Fig. 7 is a cross sectional view of the same modified device taken substantially along line

7—7 of Fig. 8 showing the inner cutter partly removed and parts thereof broken away.

Fig. 8 is a cross sectional view of the modified device taken substantially along line 8—8 of Fig. 6.

Fig. 9 is a cross sectional view of the modified device taken substantially along line 9—9 of Fig. 6.

Fig. 10 is an end elevational view of another modified form of the invention herein.

Fig. 11 is a cross sectional view thereof taken substantially along line 11—11 of Fig. 10.

Fig. 12 is a cross sectional view thereof taken substantially along line 12—12 of Fig. 11.

Fig. 13 is a view substantially like that shown in Fig. 11 but with the inner cutter partly removed and parts thereof broken away.

Fig. 14 is a cross sectional view taken substantially along line 14—14 of Fig. 11.

Like reference characters refer to like parts in all the drawings.

Referring to the drawings in detail, and particularly to Figs. 1 to 5 inclusive, a fragmentary part of an electric dry shaver well known in the art is shown, of which 10 is the motor casing and handle, 11 is the fixed outer cutter and 12 is the reciprocating inner cutter.

In Fig. 2 the motor casing 10 is broken away to reveal part of a motor well known in the art and only so much as is necessary to disclose the operativeness of the device covered by this invention. A part of the drive shaft is shown, at the outer end of which is a knurled thumb wheel 14.

Between the wheel 14 (Fig. 2) and the motor the shaft is formed with an eccentric crank portion 13. Two levers, 15 and 16, are pivoted to the motor casing 10 by a common pivot pin 17, one of which 15 has both its extremities forked. Lever 16 has only its lower extremity forked and is provided with an elongated slot 16' which engages the pivot 17. The lower forked 40 end of lever 15 straddles and engages the crank 13. The upper forked end of lever 15 straddles and engages the upper lever 16 at a point slightly above pivot pin 17. The forked extremity of lever 16 straddles and engages the lower lever 15 at a point slightly below pivot pin 17. Near the upper

end of the lever 16 are a pair of shoulders 18. 45 19 represents a spring member, the upper end of which is secured to the lever 16 at a point slightly below the shoulders 18 while the lower end of said spring member 19 is secured to the pivot pin 17 by the screw 17'. The upper lever 16 extends through a rectangular opening 20 on the extreme end of casing 10. On each side of levers 15 and 16, are the spring-pressed pins 21. The

50

lower extremities of the pins 21 are supported by a plate 22. On each of the pins 21 is a collar 23 against which springs bear to elevate the pins. Beyond the shoulders 23, each of the pins 21 is 5 of a diameter larger than the lower part thereof but not as large as the collar 23. Near the top of each of said pins 21, the wider portion thereof narrows down to a diameter approximating that of the lower portion of the pins, making virtually 10 another pair of shoulders 24. The pins 21, held secure within the casing 10 by the shoulders 23, extend through apertures 25 in the extreme upper part of casing 10. 25' represents a large rectangular groove into which the fixed outer cutter 11 is removably secured. On each end of the casing 10 are cut-out portions 26.

A detaching device 27 (Fig. 5) is made of a suitable piece of metal and is partly rectangular in shape with an ear 28 projecting outward on 20 each end thereof, which ears are curved downward at their extreme ends to form finger grips 29. In the rectangular part of the detaching device 27 are three rectangular slots. The central slot 30 has clearance enough to permit the upper lever 16 to oscillate therein though small enough to serve as a stop for the shoulders 18 of lever 16. The other two slots 31 have clearance enough for the narrow ends of pins 21 to move up and down therein though small enough to serve as 25 a stop for shoulders 24 at the top of pins 21.

The fixed outer cutter 11 has extending through the central portion of its base a rectangular slot 32, through which the upper end of lever 16 extends to engage the inner cutter 12. 30 On each side of the slots 32 are openings 33 through which the pins 21 extend. The base of said cutter 11 has a cut-in portion corresponding in shape and size to that of the detaching device 27. The end walls of the base of said outer cutter 11 have cut out portions 33' corresponding to cut-outs 26 on the casing 10.

The inner cutter has a rectangular groove 34 which engages lever 16 and on each side of said groove 34 are provided a pair of cut-ins 35 to receive the pins 21.

In the operation of the device as shown in Figures 1 to 5 inclusive, the detaching device 27 is placed in the rectangular groove 25' of the casing 10 so that the pins 21 extend through the slots 31 and the lever 16 extends through slot 30. 50 Then the inner cutter 12 is mounted within the outer cutter 11 and both together are fastened securely in the rectangular groove 25' above said detaching device 27. By twirling the knurled thumb wheel 14, the motor is started and lever 15 is given a rocking movement by means of the eccentric 13. This rocking movement is communicated by lever 15 to lever 16 which is slidably adjusted to lever 15. Lever 16 then by engagement with the inner cutter 12 causes the 55 said inner cutter to reciprocate.

By gripping the finger grips 29 with the thumb and forefinger and bearing down on them, slots 31 acting as stops for the shoulders 24 near the top of the pins 21 and slot 30 acting as a stop for the shoulders 18 of lever 16 depress the pins 21 against their respective springs and lever 16 from the positions in which they are shown in Fig. 3 to the position as shown in Fig. 4. Lever 16, being slidably mounted on lever 15, and pivot 17 as hereinbefore more fully described, is depressed against the action of spring member 19. In the position shown in Fig. 4, the pins 21 and lever 16 are released from their engagement with cut-ins 35 and groove 34 respectively of the inner

75 cutter, and the inner cutter is then free to be removed either while the motor is in operation or not.

Therefore, the advantage of this device is that it enables the operator to remove the inner cutter 5 for cleaning purposes without first having to remove the fixed outer cutter, thereby saving the operator a great waste of time and energy.

Figs. 6 to 9, inclusive represent a modified form of the same device, which differs from the device shown in Figs. 1 to 5, inclusive, only in the structure of the detaching device 27 and of the outer cutter 11. In the said modified form, detaching device 27 has a set of projections 36 on each of the longitudinal sides thereof, the said 10 projections being obliquely disposed. The said outer cutter 11 has a set of oblique cut-outs 37 15 on each of the longitudinal sides near the base thereof.

In the operation of this modified device, a finger grip 29 extending to the left as shown in Fig. 6 is pushed in. As this is done, the projections 36 engaging the cut-outs 37 cam the device 27 down whereby the slots 31 which act as stops for shoulders 24 near the top of pins 21 and slot 30 25 which acts as a stop for shoulders 18 of lever 16 force pins 21 and lever 16 to the position shown in Fig. 7. In this position the inner cutter 12 is then free to be disengaged from the outer cutter 11.

Figs. 10 to 14 inclusive, represent still another modified form of the same device. The motor driven shaft 13 extends in the direction of the longitudinal axis and has an eccentric cam 13' on its extreme upper end. Pins 21 are normal in 35 shape and have but one pair of shoulders instead of the two pairs as shown in Figs. 1 to 9, inclusive.

Positioned beneath the detaching device 27 is a plate 27' having two projections 21' resembling the ends of the usual spring-pressed pins. 40 Between the said projections 21' and in the center of said plate 27' is a projection 16' resembling the end of the upper lever 16. The lower end of projection 16' extends below the plate 27', in the center thereof, and is formed with a forked shaped projection 36'. The lower ends of projections 21' are provided with cut-outs 35'.

In operation, plate 27' is placed in the rectangular groove 25' so that the pins 21 engage the cut-outs 35' and eccentric 13' engages projection 36' leaving clearance sufficient for its 50 slideable action up and down on the said cam 13'. Then detaching device 27 is placed over plate 27' so that projections 16' and 21' extend through the slots therein and engage and groove 34 and cut-outs 35 respectively of the inner cutter.

By bearing down on the finger grips 29 with the thumb and forefinger, the pins 21 are forced down by projections 21' and projection 36 slides downward on cam 13', thereby disengaging the projections from the inner cutter which is then free 60 to be removed.

While I have described what I consider to be a highly desirable embodiment of my invention, it is obvious that many changes in form could be 65 made without departing from the spirit of my invention, and I, therefore, do not limit myself to the exact form herein shown and described, nor to anything less than the whole of my invention as hereinbefore set forth, and as hereinafter 70 claimed.

What I claim as new, and desire to secure by Letters Patent, is:

1. A dry shaving implement of the type described, comprising a grip-handle enclosing a 75

motor, a rock lever formed of an upper and lower member, said upper member being slidably mounted on and resiliently secured to said lower member, a pivot for said lower member, an elongated slot in said upper member engaging said pivot, resilient pins, shoulders on said upper member and pins, a fixed outer cutter having a recess formed in the base thereof, an inner cutter mounted in said outer cutter and adapted to be engaged by said pins and reciprocated by said upper member, and a detaching device removably secured to said grip-handle and positioned in said recess, said device being adapted to engage said shoulders to disengage said upper arm and pins from said inner cutter thereby permitting the removal of said inner cutter from said outer cutter.

2. A dry shaving implement of the type described, comprising a grip-handle enclosing a motor, a rock lever driven by said motor and formed of an upper and lower member, said upper member being slidably mounted on and resiliently secured to said lower member, a pivot for said rock lever, resilient pins, shoulders on said upper member and pins, a fixed cutter, an inner cutter mounted in said outer cutter and adapted to be engaged by said pins and reciprocated by said rock lever, and a detaching device removably secured to said grip-handle said device being adapted to engage said shoulders to depress said upper arm and pins thereby permitting the removal of said inner cutter from said fixed cutter.

3. A dry shaving implement of the type described, comprising a grip-handle enclosing a motor, a rock lever formed of a resiliently connected upper and lower member, a pivot for said lower member, an elongated slot in said upper member engaging said pivot, resilient pins, a fixed outer cutter, an inner cutter mounted in said outer cutter and adapted to be engaged by said pins and reciprocated by said rock lever, and a detaching device removably secured to said grip-handle, said upper arm and pins being adapted to be depressed by said device to permit the removal of said inner cutter from said fixed outer cutter.

4. A dry shaving implement of the type described, comprising a grip-handle enclosing a motor, a rock lever actuated by said motor and formed of an upper and lower member, said upper member being slidably mounted on said lower member, a pivot for said lower member, an elongated slot in said upper member engaging said pivot, a spring member resiliently connecting said upper member and said pivot, resilient pins, shoulders on said upper member and pins, an outer cutter having a recess formed in the base thereof, an inner cutter mounted in said outer cutter and adapted to be engaged by said pins and reciprocated by said upper member, and a detaching device removably secured to said grip-handle and positioned in said recess said device being adapted to engage said shoulders to disengage said upper arm and pins thereby permitting the removal of said inner cutter from said outer cutter.

5. In a dry shaver, a motor, a reciprocating arm actuated by said motor, a fixed outer cutter, a reciprocating cutter positioned in said fixed cutter and reciprocated by said arm, resilient pins for retaining said reciprocating cutter in said fixed cutter and means comprising a plate for disengaging said pins and arm from said reciprocating cutter to permit removal thereof from said outer cutter.

6. In a dry shaver, an inner reciprocating cutter positioned within an outer fixed cutter, driving and positioning means for said inner cutter and means comprising a plate for disengaging said driving and positioning means from said inner cutter to permit removal thereof from said fixed cutter.

7. In a dry shaver of the type described, the combination comprising a motor casing and handle, a rock lever having an upper member slidably and resiliently mounted upon a lower member, spring-pressed plungers, an inner and an outer cutter head, and a detaching device removably secured to the top of said motor casing and beneath said cutter heads affording means to disengage said upper member and plungers from the inner cutter.

8. A dry shaver comprising a motor casing and grip-handle, an outer cutter fixed to said casing, an inner cutter reciprocally mounted within said outer cutter, a rock lever comprising a lower member and upper member slidably mounted thereon and spring-pressed plungers engaging said inner cutter and means comprising a plate for disengaging said upper member and spring pressed plungers from said inner cutter to permit removal thereof from said outer cutter.

9. In a dry shaver, the combination of a motor casing, a rotatable shaft extending in the direction of the longitudinal axis of said motor casing, an eccentric cam on the upper extreme end of said shaft; a plate removably secured to the top of said motor casing, having pin shaped projections on each end of its upper face and a lever shaped projection between them, and also having a forked shaped projection on the reverse face in the center thereof, the said forked projection engaging said eccentric cam; a detaching device removably secured to said plate, and having slots through which the projections of said plate extend; a fixed outer cutter having a groove on its base to engage said detaching device; an inner cutter reciprocally mounted within the fixed outer cutter and having engagement with the projections on said plate; and finger grips on said detaching device providing means for operating said detaching device to disengage the inner cutter from the outer cutter.

10. In a dry shaver, the combination of a motor casing, a rotatable shaft extending in the direction of the longitudinal axis of said motor casing, an eccentric cam on the upper extreme end of said shaft; a plate removably secured to the top of said motor casing, having pin shaped projections on each end of its upper face and a lever shaped projection between them, and also having a forked shaped projection on the reverse face in the center thereof, the said forked projection engaging said eccentric cam; a detaching device removably secured to said plate, and having slots through which the projections of said plate extend; a fixed outer cutter having a groove on its base to engage said detaching device; an inner cutter reciprocally mounted within said fixed outer cutter and having engagement with the projections on said plate; and finger grips on said detaching device providing means for actuating said detaching device to permit disengagement of the inner cutter from said outer cutter.

11. In a dry shaver, the combination of a motor casing, a rotatable shaft extending in the direction of the longitudinal axis of said motor casing, an eccentric cam on the upper extreme end of said shaft; a plate removably secured to the top of said motor casing, having pin shaped

- projections on each end of its upper face and a lever shaped projection between them, and also having a forked shaped projection on the reverse face in the center thereof, the said forked projection engaging said eccentric cam; an outer cutter and an inner cutter, and means removably secured to said plate for disengaging the inner cutter from said lever and pin projections.
12. A dry shaving implement of the type described, comprising a grip-handle enclosing a motor, a cutting head removably secured to said handle, said head comprising a fixed cutter having a reciprocating cutter positioned therein, reciprocating means and resilient positioning means for said inner cutter, said reciprocating means being formed of an upper and lower member, and detaching means adapted to depress the upper member of said reciprocating means and said po-

sitioning means out of engagement with said inner cutter to permit withdrawal thereof from said cutting head.

13. A dry shaving implement of the type described, comprising a grip-handle enclosing a motor, a cutting head removably secured to said handle, said head comprising a fixed cutter having a reciprocating cutter positioned therein, reciprocating means and resilient positioning means for said inner cutter, cam faces cut in the lower edge of said fixed cutter, and a detaching means comprising a plate having ears thereon aligned with said cam faces, said plate being adapted to disengage said reciprocating and positioning means from said inner cutter by the cooperation of said cam faces and ears during lateral movement of said plate.

RUSSELL E. BENNER.
